UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

ACTUATING MECHANISM FOR AUXILIARY ENGINE UNITS.

Application filed December 22, 1925. Serial No. 77,158.

This invention relates to devices for actuating the pump, magneto and distributor from the internal combustion engine with which they are associated. To attain the highest efficiency in the operation of the respective units they must each be driven at a different speed. The present invention has for one of its objects to incorporate the driving mechanism for the various units into a single structure which shall be accessible, easily replaceable, compact and practical and by which the respective units shall be driven at a speed conducive to their efficient operation. Accordingly, the shafts of the various units are suitably coupled to independent shafts journaled in a housing which may be removably mounted on the engine and which may support the various units. The shafts may be driven, one from another, by gearing so proportioned as to obtain the requisite speed of rotation for each unit. A further object of the invention is to provide driving mechanism for the units which may be readily assembled and disassembled. To this end the bearings for the respective shafts are removably mounted in openings in the housing and covers or caps are so arranged as to permit the removal of the shafts when desired.

In order that the invention may be clearly understood the same will now be described more fully with reference to the accompanying drawing illustrating a preferred embodiment thereof and showing partly in side elevation and partly in vertical section driving mechanism for a pump, distributor and magneto incorporated as a unit in a housing which may be supported from the engine and which may in turn support the various auxiliary units.

An engine to which the driving mechanism according to the present invention may be applied is not illustrated in the drawings, but a spiral gear rotated by such engine is shown at a and from this spiral gear the actuating mechanism for the pump, distributor and magneto is driven. It is proposed to incorporate the driving mechanism as a unitary structure in a housing indicated as a whole at b . The housing is provided with a flange b' by which it may be removably secured to the engine adjacent the gear a . The pump is carried directly on the housing by means of the flange b^2 . The pump is not shown but a fragmentary por-

tion of its rotor shaft is indicated at c which is coupled to what may be termed the first shaft d journaled in removable bearings e, f , in the housing b . Shaft d is driven from the spiral gear a by a spiral gear g which is keyed to it and which is so proportioned as to cause the rotation of the shaft d at the most efficient speed for the operation of the pump. The magneto h is shown as carried upon a bracket b^3 integral with a closure b^4 for the opening b^5 through which shaft d and the bearings may be removed from the housing. The magneto is operatively connected as by a flexible coupling h' with a second shaft i also journaled in removable bearings j, k , in the housing b , this shaft being removable by axial movement to the left, as viewed in the drawing, through the opening b^6 closed by the cap b^7 . The magneto is driven at a higher rate of rotation than the pump. Consequently the spiral gear l carried with shaft i which meshes with gear g is of a smaller diameter than gear g so that the ratio is such as to obtain the requisite higher speed. The opening b^8 through which shaft i extends for engagement with the coupling h' may be closed by an extension b^{4x} integral with the bracket b^3 . If a distributor m is also to be driven by the driving mechanism it may be removably secured to a flat surface b^9 at the top of housing b and the distributor shaft m' may extend downwardly into a well b^{10} within the housing to be rotated from one of the shafts, say shaft i . The end of shaft m' carries a spiral gear n meshing with a spiral gear o carried on a sleeve o' keyed to shaft i and these two gears may be so proportioned as to obtain the desired speed of rotation for the distributor. If any one of the auxiliary units, for instance, the distributor, is not to be driven from the driving mechanism, a cap may be substituted therefor and secured, as by the bolt m^2 .

In disassembling the driving mechanism after the driven auxiliary units are removed either before or after the housing has been removed from the engine structure the closures b^4 and b^7 are removed. Shaft d may then be moved axially to the right through the opening b^6 , the bearing f also passing through the opening and the shaft passing through the gear g , the key d' passing along the keyway g' . After the shaft is clear of the gear the gear may be passed down-

wardly out of the housing through the well b^{10} . Shaft i is similarly removed by moving it to the left, being disengaged from the gears i and o in a manner similar to the disengagement of shaft d . To remove the distributor it is, of course, merely necessary to disengage bolt m^2 and raise the distributor in vertical direction thereby drawing the shaft m' and gear n out of the well b^{10} through the opening through which shaft m' enters.

By the construction described various auxiliary units associated with an internal combustion engine may be driven at a pre-determined speed conducive to efficient operation and the actuating mechanism is incorporated into a compact, easily demountable, unitary structure which is supported removably from the engine and in turn supports the respective units.

The invention has been described as associated with the pump, distributor and magneto of an internal combustion engine but obviously devices other than those enumerated may be driven by the mechanism.

Various modifications in the arrangement and proportion of parts will occur to those skilled in the art and no limitation in the use or the combination of elements is intended by the foregoing description and

illustration except as indicated by the accompanying claim.

What I claim is:

In a driving mechanism for auxiliary devices including pump, magneto, and distributor drive shafts, a unitary housing supporting said shafts, means for securing the housing removably to the housing of a power source, means to support the pump shaft removably in the housing, a gear carried by the pump shaft and engaging the power source, means to support the magneto shaft removably in the housing and parallel to the pump shaft, a gear on the magneto shaft meshing with the gear on the pump shaft, means for supporting the distributor shaft removably in the housing at right angles and offset with respect to the magneto shaft, means to drive the distributor shaft from the magneto shaft, a removable cap on the housing providing access to the magneto shaft, and a removable closure for the opposite side of the housing, said closure providing access to the pump shaft and a bearing for the magneto shaft and having an extension for mounting the magneto, whereby the entire assembly is mounted as a unit.

This specification signed this 9th day of December, A. D. 1925.

ALFRED F. MASURY.
